UNITED STATES PATENT OFFICE.

JOHN M. EWEN, OF CHICAGO, ILLINOIS.

METHOD OF MAKING SUBSTRUCTURES FOR BUILDINGS.

SPECIFICATION forming part of Letters Patent No. 718,441, dated January 13, 1903.

Application filed November 21, 1902. Serial No. 132,194. (No model.)

To all whom it may concern:

Be it known that I, JOHN M. EWEN, a citizen of the United States, residing at Chicago, in the county of Cook and State of Illinois, 5 have invented a certain new and useful Improvement in Processes of Making Substructures for Buildings, of which the following is a specification.

My invention relates to a process of making 10 or producing the substructures of buildings and the like. In the ordinary methods of constructing buildings the excavation is first made to the desired depth. Some kind of temporary retaining structure is put in position about the place where the excavating is 15 going on. Obviously this involves great difficulty and danger, and if the buildings surrounding the place to be excavated are heavy or if the excavation is deep injury and accident are certain to take place, and the cost 20 and delay involved in proceeding in this manner are certain to be great. When the excavation is completed, the foundations are laid both for the retaining-walls to hold up 25 the surrounding property and for the columns and the like which are to receive the weight of the building to be erected above. The increase in value of real estate is such that 30 there is a strong tendency to build not only basements, but subbasements to a depth of several "stories," so to speak. According to 35 the old method when the excavation has been completed the foundations are laid and then the structure begins to rise story by story 40 from the bottom until it reaches the street-level. In other words, the process of erecting the substructure is exactly the same as the process of erecting the upper portion of the building. I use the earth which forms, 45 so to speak, the "core" within the retaining-wall of the substructure to support and sustain the various pressures as the work progresses. I have shown diagrammatically, as it were, the application of my process in the drawings, wherein—

Figure 1 is a vertical section showing the work of producing a portion of the substructure partially completed. Fig. 2 is a similar view wherein the work has progressed farther. Fig. 3 is a similar view of the completed work. Fig. 4 is a horizontal section

showing the work in various stages of progress at different points. Fig. 5 is an enlarged detail section of the exterior retaining-wall complete.

55

Like parts are indicated by the same letters in all figures.

A A are the beams and columns of the original building; A', the floor; A², the column-foundations; A³, the curb-wall, (shown in dotted lines,) and A⁵ the sidewalk. (Shown in 60 dotted lines.)

A⁶ is the basement-space.

The first step which I take in applying my invention is to remove the curb-wall and, perhaps, the sidewalk, though the latter may be shored up and held in position in any desired manner when its supporting curb-wall is about to be removed. I now in lieu of such curb-wall erect a support B, which I hold in 70 position by means of the struts B' B'. The work to this point is of the usual type. I begin to dig a trench along the line where the exterior retaining-wall is to be placed. This trench I indicate by the letter C. As the excavation 75 of this trench proceeds I place upon each side of its walls heavy retaining-planks C' C² and hold them in proper position by means of a series of jack-screws C³. The retaining-boards may be of any length, size, or shape. The 80 number of jack-screws will be varied. When the first one has been placed in position, I make another excavation—say one foot deep—in said trench and place another set of boards with the proper number of jack-screws. Thus 85 I continue the work until the trench is dug the desired depth. I now place in the bottom of this trench a footing C⁴, preferably of concrete. It will be understood that as much or as little as may be convenient of such 90 trench may be dug out at one time, or the entire trench all the way around the proposed building-site may be simultaneously excavated. I now place permanent I-beams C⁵ vertically in the trench, putting them along 95 at proper intervals, as indicated in Fig. 4, and preferably between the jack-screws C³. With each of these I-beams I associate a series of short jack-screws C⁶—one on each side of the beam and bearing, respectively, against 100 the boards C' and C². As this work is carried forward it is obvious that the jack-screws

C^3 can be removed, as indicated in Fig. 4. The connection at the corner may be made in various ways. I have illustrated one form.

D is the short board placed diagonally across the corner; D' , a block on which rests the longer jack-screw D^2 , the other end of which rests upon the cross-block D^3 in the exterior corner of the trench. Obviously up to this point the conditions of stress and pressure between the earth exterior to the proposed building and the core of earth on the site of the building are practically undisturbed and whatever weight there was on the exterior—as, for example, the weight of some building—is properly sustained against the core of earth within the building-site. The pressure is taken up by the jack-screws and then by the shorter jack-screws, which act through the vertically-arranged I-beams. The space between the I-beams is now filled with concrete E in any desired manner, so as to form an exterior retaining-wall of steel and concrete, and this wall may surround the entire building-site.

I now proceed to make the excavation for the columns. This I do by boring through the earth and retaining the earth in any desired manner—as, for example, by means of the rings F F' . These rings may be associated with vertical stays or utilized in any manner to hold the earth against the pressure which may be applied to it from any source. This work is carried down to preferably the solid rock or until at least a proper foundation is obtained. The bottom of this hole is then properly filled with concrete F' , and the column-foothing F^2 is placed in position. A column F^3 is now inserted in this hole within the rings, and it is supported upon the concrete F' and the footing F^2 in proper manner. In cases where, as here illustrated, the substructure is two or three or more stories in depth the column must be properly supported or stayed, because it is intended to or may carry a considerable load before the excavation is made, as hereinafter explained. This I do by throwing out from the column at suitable intervals supports against the inner walls of the rings. These supports may be short jack-screws F^4 F^4 , and they may be arranged as frequently as desired, but should be placed in proximity to the horizontal line of each proposed cross-beam, so as to give the column suitable strength against any tendency which it might develop to buckle under a load. Having proceeded thus far, it will be possible to begin the upper structure, and this is done by forming the first horizontal floor-support. This is done by putting in position the I-beams G G' G^2 and the like and suitably attaching them to the upper end of the exterior vertical I-beams C^5 and to the columns. Obviously prior to this action the columns and beams A , floor A' , and footing A^2 of the old building will have been removed. A little further excavating will uncover one or two of the upper

boards C' , and the second layer of floor-supports are now put in—for example, beams G^3 G^4 G^5 —and they are properly attached to the respective columns and to the exterior retaining-wall. These beams will form the floor of the basement. The earth for the subbasement may now be removed, the parts being sufficiently supported by the beams, columns, and retaining-walls, which are bolted together. Of course in this process the upper boards C' , with the inner short jack-screws C^6 , will be removed. This process of excavating will continue until the floor-line of the subbasement is reached, when the supports for such subbasement-floor will be placed in position. These beams are indicated by G^6 G^7 G^8 . They are in like manner bolted to the exterior walls and the columns. In the same manner the cellar excavation is made, and the floor of the cellar G^9 can then be placed in position. Thus there will be constructed within the retaining-wall, but securely supporting the same by reason of the lateral beams, a steel structure which will constitute the substructure of the building and which will be entirely surrounded, if this be desired, by a retaining-wall of steel and concrete. This retaining-wall will be coated on the inside in any desired manner by cement or the like at J . Its exterior is also properly coated at J' and then, if desired, is further covered by layers of asphalt J^2 . The short jack-screws on that side are then removed one by one, and the space between the boards C^3 and the retaining-wall is filled up with crushed stone J^3 or suitable filling material. Of course the boards C' and C^2 will be taken out during the process and the struts B' will be removed at the proper time. When the whole process has been completed and the entire structure has been finished, it will be found that there is an exterior wall of vertical I-beams and concrete around the building-site and that it is securely attached to and forms part of the structure of the building. This retaining-wall is held in position by the cross-beams and may present a vertical interior face, as indicated, if desired. It may thus be said that the exterior pressure on one wall is balanced, as it were, by the exterior pressure on the opposite wall by means of the beams C^3 C^4 , &c. The sidewalk K will be properly supported upon the beams G , and the pavement K' will be extended out over the vertical layer of crushed stone or filling material up to the sidewalk. In the lower part of this crushed stone or filling material is preferably placed the drain-tile K^2 , which is connected with the intake K^3 and whence the water which may accumulate in such drain-tile may be carried off in any desired manner. It is obvious that this substructure may be carried downward to any desired depth and that it is a perfectly safe method, because the inner core of earth carries the same load or sustains the same pressure at all times during the process.

of the work except as to certain minute areas which are exposed from time to time as the jack-screws are moved. This, however, is a negligible danger, and if there is any shifting of position the new jack-screw placed in position at or near the point from which the old jack-screw was removed can be operated to restore original conditions. These several jack-screws are used because they present adjustable features which permit the work to be adjusted as it progresses, and in the operation of a large building would be constantly attended and operated so as to keep the condition substantially uniform.

As previously suggested, my process is used in gradually sinking or excavating a trench where the retaining-wall is to be placed and simultaneously supporting the earth to be held up by the retaining-wall against the earth within the retaining-wall by means of the removable and adjustable jacks. As the trench is deepened the supporting devices are supplied until the full depth of the excavation is reached. I now proceed to construct or erect the retaining-wall, and its several members while in process of being assembled serve as intermediaries between the two masses of earth to transmit the pressure from the exterior earth to the interior earth or core, and thus I practically complete the retaining-wall. Such a retaining-wall would obviously be insufficient to permanently maintain itself against the exterior pressure when the earth core is removed. I therefore construct within the earth core those parts of my substructure which are to take the pressure from above, and while so doing I support the excavations for such column-like parts, so as to keep the core of earth intact, and I also support the columns within such excavations by lateral stays or struts, so as to prevent them from buckling if any considerable weight should be applied to them. I complete the internal framework of the structure by connecting its horizontal portions from column to column and from the columns to the retaining-wall, and as this process continues I excavate the core to make room for such laterally-projecting frame members.

To point out the value and the use of my invention, it is only necessary to suggest that any kind of a retaining-wall can be built according to my process. The wall may be thin, as I have indicated, and of uniform thickness, as I have indicated, and may be a dependent wall, as indicated—that is, a wall which is not self-supporting against external pressure. On the other hand, the wall may be of any desired thickness and of variable thickness and may be made of any desired materials and may be a self-supporting retaining-wall of the ordinary type or pattern, wide at the bottom and narrow at the top.

It is obvious that, as previously suggested, the superstructure may be erected on the columns before the substructure is completed, and even, if desired, long before the excava-

tion is completed—that is, the excavating can take place at any time and under any desired conditions. On the other hand, it is equally obvious that these retaining-walls and the remainder of the substructure can be erected under a completed building. Thus by the use of my process it is entirely feasible to erect under a standing building which is to be preserved a new retaining-wall and a new substructure, and this may be done at any time and without disturbing the occupants of the building above. One advantage in working under an old building in position or erecting the substructure first is that the excavating can then be more conveniently carried on, because of the protection furnished by the superstructure and because of the ease with which the hoisting and other working apparatus can be attached to such superstructure. Of course the wall may be wholly or partially completed at any time, and in some instances it may be desirable to have only a portion of a retaining-wall complete according to my system, though when the system is fully applied there should be a retaining-wall entirely around the area above which the building is to be erected. I have used the terms "inside" and "outside" and other like terms in their ordinary senses and I have used the word "core" as applied to the earth within the retaining-wall, and whether the wall be completed or not it refers to some or all of the earth which lies under the building to be erected and which receives the external lateral pressure, as described. It will be observed that, as above suggested, this method provides for ample security and makes the work thoroughly safe from liability of injury to adjoining property. At the same time it is evident that there is a great saving of time, both because the work can be begun before the old building is destroyed or its occupants disturbed and because in a sense the builder can build in both directions from the floor-level at the same time and because the retaining-wall having been built before the old building is removed it is possible to proceed at once upon the removal of the old building to the erection of the foundation for the vertical members which are to sustain the superstructure.

I have shown the application of my process wherein the wall is placed midway between the two trench-linings, though of course for certain purposes it might be placed at one side, and it might be placed against the inner lining, thus leaving room between the wall and the outer lining for the further carrying out of the process.

In my description and claims I have necessarily recited the several steps in succession, although it will be understood and for the most part is obvious that the precise order of the several steps might be varied without departing from the spirit of my invention and that some of the steps recited successively might be carried on simultaneously.

I claim—

1. The process of making and placing in position substructures for buildings and the like, which consists in forming a suitable trench where the exterior wall is to be erected, and simultaneously placing in position a lining for said trench, from the top downward, as the work of forming the trench progresses, then placing braces between the two linings, so as to transmit the exterior pressure to the core of earth within such proposed wall, and then erecting within the trench a wall of less thickness than the width of the trench.
2. The process of making and placing in position substructures for buildings and the like, which consists in forming a suitable trench where the exterior wall is to be erected, and simultaneously placing in position a lining for said trench, from the top downward, as the work of forming the trench progresses, then placing braces between the two linings, so as to transmit the exterior pressure to the core of earth within such proposed wall, then erecting within the trench a wall of less thickness than the width of the trench, and as the wall progresses, substituting for the braces between the two linings braces between one of the linings and the wall, then finishing the exterior surface of such wall to make it as nearly as possible impervious to moisture, and filling in between such surface and the opposed trench-surface with permanent material, and removing the braces and lining from the bottom up.
3. The process of making and placing in position substructures for buildings and the like, which consists in forming a suitable trench where the exterior wall is to be erected, and simultaneously placing in position a lining for said trench, from the top downward, as the work of forming the trench progresses, then placing braces between the two linings, so as to transmit the exterior pressure to the core of earth within such proposed wall, then erecting within the trench a wall of less thickness than the width of the trench, then finishing such wall on one of its surfaces opposed to the trench-surface so as to make it as nearly as possible impervious to moisture.
4. The process of making and placing in position a substructure for buildings and the like, which consists in forming a suitable trench where the exterior wall is to be erected, and simultaneously placing in position a lining for said trench, from the top downward, as the work of forming the trench progresses, then placing braces between the two linings, so as to transmit the exterior pressure to the core of earth within such proposed wall, then erecting within the trench a wall of less thickness than the width of the trench, then filling in between the exterior surface of the wall and the opposed surface of the trench, and at the same time removing the braces.
5. The process of making and placing in position substructures for buildings and the like, which consists in forming a suitable trench where the exterior wall is to be erected, and simultaneously placing in position a lining for said trench, from the top downward,
- as the work of forming the trench progresses, then placing braces between the two linings, so as to transmit the exterior pressure to the core of earth within such proposed wall, then erecting within the trench a wall of less thickness than the width of the trench, then simultaneously removing the braces and lining and filling in with permanent material between the exterior surface of the wall and the opposed surface of the trench.
6. The process of making and placing in position substructures for buildings and the like, which consists in forming a suitable trench where the exterior wall is to be erected, and simultaneously placing in position a lining for said trench, from the top downward, as the work of forming the trench progresses, then placing braces between the two linings, so as to transmit the exterior pressure to the core of earth within such proposed wall, then erecting within the trench a wall of less thickness than the width of the trench, and as the wall progresses, substituting for the braces between the two linings braces between one of the linings and the wall, then finishing the exterior surface of such wall to make it as nearly as possible impervious to moisture, and filling in between such surface and the opposed trench-surface with permanent material, and removing the braces and lining from the bottom up.
7. The process of making and placing in position substructures for buildings and the like, which consists in forming a suitable trench where the exterior wall is to be erected, and simultaneously placing in position a lining for said trench, from the top downward, as the work of forming the trench progresses, then placing braces between the two linings, so as to transmit the exterior pressure to the core of earth within such proposed wall, then erecting within the trench and free from the lining, wall members, and substituting for the braces between the linings braces between such wall members and the lining, and then completing the wall in connection with such wall members.
8. The process of making and placing in position substructures for buildings and the like, which consists in forming a suitable trench where the exterior wall is to be erected, and simultaneously placing in position a lining for said trench, from the top downward, as the work of forming the trench progresses, then placing braces between the two linings, so as to transmit the exterior pressure to the core of earth within such proposed wall, then erecting within the trench a wall of less thickness than the width of the trench, then inserting between such wall and the surface of the trench means for transmitting the exterior pressure to such wall, and then inserting between two such walls or wall portions braces which connect them so that the exterior pressure on one wall is balanced by the exterior pressure on the other wall.
9. The process of making and placing in po-

sition substructures for buildings and the like, which consists in forming a suitable trench where the exterior wall is to be erected, erecting a wall in said trench so as to 5 transmit the exterior pressure through said wall to the core of earth on the opposite side of the wall, then providing on the opposite side of said core of earth a wall which receives the pressure exterior to it, then simultaneously removing the core of earth and substituting therefor cross-braces which connect 10 said walls and balance the exterior pressure against one of them with the exterior pressure against the other.

15 10. The process of making and placing in position substructures for buildings and the like, which consists in forming a suitable trench where the exterior wall is to be erected, and simultaneously placing in position a 20 lining for said trench, from the top downward, as the work of forming the trench progresses, then placing braces between the two linings, so as to transmit the exterior pressure to the core of earth within such proposed 25 wall, then erecting within the trench a wall, then substituting for the core of earth within such proposed wall suitable permanent braces to take the exterior pressure transmitted through the wall.

11. The process of making and placing in 30 position substructures for buildings and the like which consists in erecting the exterior wall of the substructure and associating therewith throughout the process of construction means for transmitting the exterior 35 pressure to the core of earth within the proposed wall, such means operating through the completed wall, then simultaneously removing the core and replacing it with cross-braces to receive the pressure theretofore received by such core.

12. The process of making and placing in 40 position substructures for buildings and the like, which consists in forming a suitable trench where the exterior wall is to be located, supporting the external pressure on the outside of such trench against the core of earth on the opposite side of the trench, and then erecting in the trench a retaining-wall 45 free from the side surface of the trench, and supporting the external pressure on the core of earth through such retaining-wall as a transmitting medium.
